(57) **CLAIM**

The ornamental design for a power distribution box, as shown and described.

DESCRIPTION

FIG. 1 is a perspective view of a power distribution box according to the present invention;

FIG. 2 is a left side elevational view of the power distribution box of FIG. 1;

FIG. 3 is a right side elevational view of the power distribution box of FIG. 1;

FIG. 4 is a rear elevational view of the power distribution box of FIG. 1;

FIG. 5 is a front elevational view of the power distribution box of FIG. 1;

FIG. 6 is a top plan view of the power distribution box of FIG. 1; and,

FIG. 7 is a bottom plan view of the power distribution box of FIG. 1.

No claim is made to the number of and locations of outlets, breakers, and receptacles on the side panels.

The dashed lines illustrate environment that does not form a part of the present invention, and no claim is made to the material illustrated with dashed lines.

1 Claim, 7 Drawing Sheets
